ELBERT KELLY, OF ANNISTON, ALABAMA.

LAP LINK.

Application filed September 30, 1925. Serial No. 59,586.

My invention relates generally to improvements in draft gear for plows and like agricultural implements, and more particularly to a lap link which is adapted to be included in such draft gear, and consists in the combinations, constructions and arrangements herein described and claimed.

An object of the invention is to provide a lap link which is adapted to connect a 10 whiffle-tree hook or like connection with a clevis or like connection at the end of the beam of an implement of any one of a plurality of types of construction.

A further object of the invention is to 15 provide a lap link which is adapted to connect a vertically disposed hook or ring with either a horizontal or vertical ring or the like.

A further object of the invention is to 20 provide a lap link of the character described which is adapted to transmit power or motion therethrough between two parts connected thereby without any side draft on the part to which the power or motion is 25 transmitted.

A further object of the invention is to provide a lap link which is of simplified construction, which is not likely to be accidentally disengaged from the parts which it 30 may connect, and which is thoroughly practical commercially.

Other objects and advantages will be apparent from the following description, considered in conjunction with the accompanying 35 drawings, in which:

Figure 1 is a perspective view showing a lap link embodying the invention, establishing connection between a whiffle-tree and a plow beam,

Figure 2 is a view mainly in plan and partly in horizontal section, showing a portion of the structure exhibited in Figure 1, and

Figure 3 is a perspective view of the lap link.

In carrying out my invention, I make use of a length of steel wire or other similar material which possesses considerable inherent strength. This length of wire is bent 50 intermediate its ends substantially into U-shape to provide a half loop indicated at 1 having a pair of side members or arms 2 and 3, respectively. The members 2 and 3 are bent into U-shape adjacent to their extremities to provide hooks indicated at 4 and 5,

respectively. The end portion of the arm 2 is bent downwardly and rearwardly to form the hook 4, while the corresponding end portion of the arm 3 is bent laterally outward and rearward to form the hook 5, whereby 60 the hook 4 will be vertically disposed with the bill portion thereof downward and the hook 5 will be horizontally disposed with the bill portion thereof at the outer side thereof. The bill portions of the hooks 4 65 and 5 terminate substantially flush with each other.

The hooks 4 and 5 are adapted for engagement with connections which lie in planes extending at right angles to each other. The 70 hooks 4 and 5 are spaced apart and held against spreading and the entrances thereto are closed by a slidably latching member 6. The latter comprises a substantially L-shaped or angular strip of any suitable material, such as relatively stiff leather or resilient metal. One arm of the angular strip 75 6 is longer than the other arm and is provided with a slot or elongated aperture 7 through which the hook 5 extends, the end 80 of the bill portion thereof terminating in the slot. The shorter arm of the angular strip 6 is provided with a slot or elongated opening 8 which lies in a plane extending at right angles to that of the slot or elongated 85 opening 7, and through which the hook 4 extends, the end of the bill portion of the hook 4 terminating in the slot 8. A pin 9 extending vertically through the longer arm of the strip 6 and through an opening in a 90 laterally widened portion 10 of the inner arm or body of the hook 5 secures the strip 6 against sliding on the arm 3 and tends to hold the longer arm of the strip and the shorter arm of the strip in closing relation 95

to the hooks 5 and 4, respectively. Since the strip 6 is made of a material which possesses inherent resiliency and is flexible, the free end portion of the longer arm of the strip may be flexed to expose the free end of the outer arm or bill of the hook 5, so that the latter 100 may be engaged with or disengaged from a suitable connection. The shorter arm of the strip 8 likewise may be flexed to expose the free end of the lower arm or bill of the hook 4 so that the latter may be engaged with or disengaged from a suitable connection. If required, the free end of the shorter arm of the strip 6 may be flexed to an extent sufficient 105 to temporarily disengage the hook 4, 110

so that a ring or like suitable closed connection may be placed in engagement with or disengaged from the half loop 1.

When the free portions of the latching strip 8 have not been flexed from the positions exhibited in Figure 3, the bend portion of the half loop 1 will extend laterally of one face of the strip 6, while the hooks 4 and 5 will extend laterally of the opposite 10 face of the strip.

From the foregoing description of the various parts of the device, the operation thereof may be readily understood. When it is desired to connect parts having attaching portions or members lying in parallel planes, the half loop 1 and the hook 5 are employed while the half loop 1 and the hook 4 are employed when it is desired to connect parts having attaching portions or members 15 lying in planes extending at right angles to each other. In Figure 1, I show a plow having a beam 13 provided at its free end with a clevis or attaching portion 14 having a vertical series of horizontal openings 20 15 (Fig. 1). A whiffle-tree 16 is provided with a hook 17 which is vertically disposed. The hook 17 is engaged with the half loop 1 and the hook 5 is inserted in any one of the 25 openings 15 to connect the whiffle-tree with the plow beam. Since a pull transmitted from the whiffle-tree through the half loop 1 and the hook 5 to the plow beam will be transmitted along the arm common to the half loop 1 and hook 5, it will be manifest 30 that no side draft on the plow beam will result from a straight forward pull on the whiffle-tree hook.

It will be understood from the foregoing 35 that the vertically disposed whiffle-tree hook 40 17 may be connected with a horizontal series of vertical openings in a clevis or attaching portion of a plow beam by making use of the half loop 1 and hook 4, the whiffle-tree hook then being engaged with the half loop 45 1 and the hook 4 being engaged with any one of the vertical openings of the horizontal

series in the attaching portion or clevis of the plow beam.

The inherent resiliency of the latching strip 6 and the frictional engagement thereof with the hooks 4 and 5 will tend to hold the 50 free portions of the strip in position to close the hooks 4 and 5 at the normally open ends of the latter so that accidental disengagement from the part with which either of the hooks 4 and 5 is connected is precluded. 55

Obviously many modifications and adaptations of the form of the device disclosed herein may be provided and I therefore consider as my own all such modifications and adaptations as fairly fall within the scope 60 of the appended claims.

I claim:—

1. A lap link comprising a pair of substantially U-shaped hooks constituting attaching portions, one arm of each of said hooks being longer than the other arm thereof, a half loop having arms into which the longer arms of said hooks are merged, the free ends of the hooks terminating substantially flush with each other, and a latching member for closing said half loop and said hooks, said loop and said hooks extending in opposite directions. 70

2. A lap link comprising two substantially U-shaped hooks, a half loop merging the adjacent arms of said hooks each into the other and extending beyond a line extending transversely between the free ends of said hooks, and a flexible and resilient latching member having slots receiving the end portions of said hooks and said half loop, said latching member being secured to the body of one of said hooks, whereby the portions of the latching member in engagement with the arms of said hooks will normally remain 80 in position to close said hooks and may be flexed from such position to permit the hooks to be engaged with or disengaged from suitable connections. 85

ELBERT KELLY.
